GEORG KIRKEGAARD, OF NEW YORK, N. Y.

MACHINE FOR CAPPING BOTTLES.

No. 844,144.

Specification of Letters Patent.

Patented Feb. 12, 1907.

Application filed January 2, 1906. Serial No. 294,064.

To all whom it may concern:

Be it known that I, GEORG KIRKEGAARD, a citizen of the United States, residing at the city of New York, in the borough of Brooklyn and State of New York, have invented certain new and useful Improvements in Machines for Capping Bottles, of which the following is a full, clear, and exact description.

My invention relates to a machine for capping bottles, and pertains particularly to the application of bottle-caps of the class set forth in Letters Patent No. 796,734, comprising a cork-lined disk with depending fingers, which are adapted to be pressed into locking engagement with the neck of a bottle by the circumferential movement of a clamping-ring. In the present application I have set forth a machine for applying caps of this class quickly and efficiently and in a direct and positive way.

One of the objects of the present invention is to render the insertion of the cap into the machine more easy to accomplish.

A further object of the invention is to provide a construction operated by foot-power, which, however, is so arranged as to secure abundant power for rotating the clamping-ring in locking the cap to the bottle.

With these and other objects in view my invention consists in the construction, combination, location, and arrangement of parts hereinafter set forth and shown, and finally particularly pointed out in the appended claims.

In the drawings, Figure 1 is a side elevation showing a complete machine embodying the principles of my invention. Fig. 2 is a front view of the same. Fig. 3 is a section upon the line III III of Fig. 1. Fig. 4 is a detail view, partly in section, of the main operating-spindle. Fig. 5 is a detail side view of the same, taken at right angles to the plane of Fig. 4. Fig. 6 is a view on the line VI VI of Fig. 1 looking downward. Fig. 7 is a detail view of a portion of the main operating-spindle in a different position from that of Fig. 4. Fig. 8 is a section on the line VIII VIII of Fig. 4. Fig. 9 is a detail sectional view on the line IX IX of Fig. 4. Fig. 10 is a detail view showing part of the mechanism of Fig. 9.

In carrying out my present invention I make use of a main operating-spindle having a cap-applying head, which is positively depressed upon a bottle, so as to engage a cap in sealing relation therewith. In addition to the positive means for depressing the cap

upon the bottle I provide rack-and-pinion means for non-positively rotating the clamping-ring, so as to lock the cap in place. The particular character of the non-positive connection for rotating the clamping-ring comprises a volute spring in the present case which is sufficiently resilient to yield slightly in case irregularities in the bottle or in the manufacture of the cap cause an abnormal resistance.

Referring to the drawings, in which like parts are designated by the same reference-sign, 1 denotes a main frame or casing in the form of a hollow vertical standard supported from the floor by a base portion or flanges 2. The standard is conveniently made hollow throughout the greater portion of its length, so as to contain and guide a vertically-reciprocating rod 3, to the lower end of which is attached the foot-pedal 4, pivoted at 5 upon the main frame.

6 6 denotes a tension-spring attached to the foot-pedal 4 and serving to normally return the same upward.

7 7 denotes the main operating-spindle guided to reciprocate vertically in bearings 8, projecting from the main standard 1 and having a lever connection 9 with the vertical rod 3, so as to be reciprocated thereby. 8 8 These details of construction by which the main operating-spindle 7 is supported and moved constitute a convenient practical arrangement; but I do not desire to be limited or restricted thereto, since any form of guiding and operating means may be used in lieu thereof.

9 9 The main operating-spindle 7 has a threaded connection 10 with the lever 9, which is adjustable outward from the spindle, so as 95 to vary the field of movement thereof. The lower end of the spindle has an axially-movable independently-revolvable core 11, normally spring-pressed outward therefrom. The lower end of the core is axially drilled to 100 form a hole or chamber 11'. In this chamber is guided to reciprocate a plunger 12, constantly pressed outward by the spring 13 and carrying at its lower end a bearing-support 14, which is hollowed, as shown at 15, 105 on its lower face, so as to receive a bottle-cap. Instead of forming the plunger 12 with straight cylindrical walls I cut an annular groove or recess 16 therein, having a square upper face or shoulder 17 and a curved or beveled lower wall 18.

11 19 denote dogs having rounded ends and

guided to have a slight radial movement within the core 11. These dogs bear with their inner ends against the plunger 12 and contact at their other extremities with depending pawl-levers 20, pivoted at 21 upon the core 11.

22 denote springs upon the core 11, which serve to normally press the pawl-levers 20 radially outward. The lower ends of the 5 pawl-levers are formed with offset teeth or edges 23, the purpose of which are to engage the milled edges of the usual clamping-ring of a bottle-cap. In addition to the depending pawls 20 I provide depending spring-fingers 24, having notched extremities 25 and spaced annularly around the spindle, so as to receive and hold a bottle-cap.

I provide means for rotating the core 11 independently of the main operating-spindle 7, and for this purpose I form a splined groove 26 upon the side of the core 11, which coöperates with a correspondingly-splined beveled gear 27, which is guided by a bracket 28 from the main frame or standard 1.

25 29 denotes another beveled gear meshing with the gear 27 and loosely resting on a horizontal stud or axis 30, projecting from the main frame. The stud or axis 30 is fixed with relation to the main frame and carries 30 loosely upon it a gear 31, meshing with a rack-section 32, guided to reciprocate vertically in the machine.

33 designates a cross-head by which the rack-section 32 is rigidly connected to the main operating-spindle 7. The face of the gear 31 has a lug or projection 34 thereon, and the beveled gear 29 also has a lug or projection 35, which is in the path of and adapted to be engaged by the lug or projection 34.

40 The beveled gear 29 has a spring connection with its supporting-shaft 30, comprising a volute or spiral spring 36, having its ends respectively secured to the gear 29 and to the stud or shaft 30.

45 As above stated, the stud or shaft 30 is stationary, and the bevel-gear 29 is loose on the shaft and spring-pressed rotarily by its volute spring 36. I provide a stop to limit the movement of the bevel-gear under the 50 action of its volute spring, conveniently formed by a pin 37 on the stud or shaft 30 and located in the path of a lug 38 on the bevel-gear. In the normal relation of the parts the bevel-gear is pressed by its volute 55 spring into its limiting position with the lug 38 against the pin 37.

The operation is as follows: The operator being provided with a supply of filled bottles and caps to be applied, places 60 the bottles upon a supporting mat or pad 39 in axial alinement with the main operating-spindle. The operator now pushes a cap upward between the depending fingers 24 until it engages the bearing-support 14, whereupon the edge of the clamping-ring will be en-

gaged by the notches 25. During this time the main operating-spindle is in its raised position, so that the core 11 is spring-pressed to its outward limit of movement therefrom, and the plunger 12 is also spring-pressed to its outward limit of movement from the core. The relation of the plunger and core is illustrated in Fig. 7, from which it will be seen that the dogs 19 lie in the annular groove 16 of the plunger, so that the pawl-levers 20 are thrown radially outward, by their springs 22. The object of this construction is to throw the pawl-levers outward, so as not to impede or interfere with the insertion of the caps into the machine. The operator now places his 80 foot upon the pedal 4 and depresses it, so that the motion is communicated to the main operating-spindle. The main operating-spindle descends, carrying with it the core 11 and the plunger 12 until the cap 85 rests upon the bottle. The main operating-spindle continues to descend, however, initially compressing the spring 13, so that the pawl-levers 20 move inward and engage the usual clamping-ring of the cap with their 90 toothed edges 23. This occurs by virtue of the camming action of the curved or beveled wall 18 of the plunger 12 upon the dogs 19. As the main operating-spindle continues to descend still farther the core 11 is axially 95 pressed inward with respect thereto against its resilient support, so that a considerable amount of pressure is transmitted to the cap to press the latter in proper sealing relation upon the bottle. In this movement the rack-section 32 rotates the gear 31, so that the lug 34 moves in the direction of the arrow in Fig. 9; but this motion is not transmitted to the beveled gear 29, since there is no connection between the two. After a certain movement 100 the lug 34 rotates sufficiently to contact with the lug 35 of the gear 29, which is thereupon moved by the engagement, rotating the gear 27, the splined core 11, and the pawl-levers 20. These being in engagement with the 105 usual milled ring of the bottle-cap, the latter is turned so as to lock the cap upon the bottle. On account of the swiveled nature of the connection of the bearing-support 14 with the core 11 the bearing-support 14 does 110 not partake of the motion of the core, but remains immovable upon the bottle-cap. The cap is now completely locked in proper sealing relation upon the bottle, and the bottle may be removed by releasing the pressure on 115 the pedal 4, which permits the main operating-spindle to ascend and all the parts to perform a reversal of their former movement. When pressure is released from the foot-pedal 4, the main operating-spindle 7 ascends, and 120 such movement effects a reverse rotation of the spur-gear 31. Now at this time the lug 35 on gear 31 has been rotated into its extreme position, in which it has contacted 125 with the lug 34 of the bevel-gear and carried 130

this around, as above stated. The return movement of spur-gear 31 is therefore accompanied by a following movement of the bevel-gear impelled by its volute spring; but the 5 movement of the bevel-gear is arrested finally by engagement of the pin 37. Thereafter the spur-gear continues its movement independently of the bevel-gear. In other words, the main operating-spindle in its upward 10 movement first causes a reverse rotation of the cap-applying head, and afterward the cap-applying head moves upward with the spindle, but without rotation.

What I claim is—

15 1. In a bottle-capping machine, a main operating-spindle having an independently-revolvable core spring-pressed outward therefrom, means for depressing the spindle, and rack-and-pinion connections for rotating the 20 core after a predetermined movement of the spindle.

25 2. In a bottle-capping machine, a main operating-spindle arranged to be depressed upon a bottle, a core spring-pressed outward therefrom and having means for holding a cap thereon, and rack-and-pinion connections for rotating the core after a predetermined movement of the spindle.

30 3. In a bottle-capping machine, a main operating-spindle arranged to be depressed upon a bottle, a core spring-pressed outward therefrom and having means for engaging the cap, and rack-and-pinion connections for rotating said core after a predetermined 35 movement of the spindle.

40 4. In a bottle-capping machine, a main operating-spindle arranged to be depressed upon a bottle, a core spring-pressed outward therefrom, a rack depending from the spindle, a gear arranged to be turned by said rack, and connections from said gear for rotating the core after a predetermined movement of the spindle.

45 5. In a bottle-capping machine, a main operating-spindle having a core spring-pressed outward therefrom, a bevel-gear splined to said core, a second bevel-gear engaging said first-named gear and having a lug thereon, a spur-gear having a lug cooperating with that of the bevel-gear, and means for imparting movement to said spur-gear whereby the bevel-gear and core are rotated 50 after a predetermined movement thereof.

55 6. In a bottle-capping machine, a main operating-spindle having a core spring-pressed outward therefrom, a bevel-gear splined to said core, a second bevel-gear having a lug, a spur-gear having a lug arranged to contact with that of the bevel-gear after a 60 predetermined movement, spring means for normally positioning the bevel-gears, and rack connections from the main operating-spindle for rotating them after a predetermined movement of said spindle.

65 7. In a bottle-capping machine, a main

operating-spindle having a core spring-pressed outward therefrom, and bevel-gear connections for imparting a rotary movement to said core after a predetermined movement of the spindle.

70

8. In a bottle-capping machine, means for engaging and supporting a cap, pawl-levers arranged in normally spread-apart relation, means for contracting said pawl-levers upon a bottle-cap when the latter is pressed upon a 75 bottle, and means for subsequently rotating the levers bodily about a central axis to lock the cap to the bottle.

9. In a bottle-capping machine, means for engaging and supporting a cap, pawl-levers 80 normally held out of contact therewith, means for contracting said pawl-levers upon the cap when the latter is depressed upon the bottle, and means for subsequently turning the levers upon a central axis to lock the cap 85 to the bottle.

10. In a bottle-capping machine, means for engaging and supporting a cap, pawl-levers normally out of contact therewith, cam means for contracting said levers upon the 90 cap when the latter is pressed upon a bottle, and means for subsequently turning the levers upon a central axis to lock the cap to the bottle.

11. In a bottle-capping machine, a vertically-depressible core having a plunger spring-pressed outward from its lower end, a bearing-plate on said plunger, pawl-levers, and cam means on said plunger for moving said pawl-levers into contact with the 95 bottle-cap.

12. In a bottle-capping machine, a vertically-depressible core having a plunger spring pressed outward from its lower end, a bearing-plate on said plunger, spring-fingers 105 depending from said bearing-plate, pawl-levers on said core, and cam means on said plunger for moving said pawl-levers into contact with the bottle-cap.

13. In a bottle-capping machine, a de- 110 pressible main operating-spindle, a rack secured thereto, a spur-gear in mesh with said rack and having a lug, a bevel-gear loosely supported adjacent to said spur-gear and having a lug in the path of the lug on said 115 spur-gear, a volute spring for normally positioning said beveled gear, a core projecting from the main operating-spindle, a bevel-gear splined to said core and in mesh with said first-named bevel-gear, and means on 120 said core for holding a bottle-cap, whereby the cap is initially depressed and subsequently rotated upon a bottle.

In witness whereof I subscribe my signature in the presence of two witnesses.

GEORG KIRKEGAARD.
